United States Patent Office.

WALTER K. MARVIN, OF NEW YORK, N. Y.

Design No. 3,772, dated November 30, 1869.

DESIGN FOR A SAFE.

The Schedule referred to in these Letters Patent and making part of the same.

To all whom it may concern:

Be it known that I, WALTER K. MARVIN, of New York, county of New York, and State of New York, have invented a new and original Design for Safes; and I hereby declare the following to be a full, clear, and exact description of the same, reference being had to the accompanying drawing.

This design, which is intended to be applied to the panels of safes, consists of an exterior rope moulding, so called, with acanthus-shaped ornamentations applied to the same, in the manner represented in drawing. With this may be combined a plain inner moulding, having at its top and bottom an acanthus-shaped ornament, from which springs a bunch of grapes or

other fruit, leaves, or other ornament of a similar character, giving a fitting termination to the acanthus.

The design is applied to any portion of the safe, preferably to the two sides and the front, and can be gilded, bronzed, or otherwise colored to harmonize with the color of the main portion of the safe.

What I claim as my invention, and desire to secure by Letters Patent, is—

The design for safes, as herein shown and described.

In testimony whereof, I have hereunto set my hand, in the presence of two subscribing witnesses.

Witnesses: WALTER K. MARVIN.

M. BAILEY,
WM. H. McCABE.
